(57) **CLAIM**

The ornamental design for a car roof article holding case, as shown and described.

DESCRIPTION

FIG. 1 is a perspective view of a car roof article holding case, wherein the dashed lines represent a zipper covered underneath a rim portion of the holding case;

FIG. 2 is a front view thereof, wherein the dashed lines represent a zipper covered underneath a rim portion of the holding case;

FIG. 3 is a back view thereof, wherein the dashed lines represent a zipper covered underneath a rim portion of the holding case;

FIG. 4 is a left side view thereof;

FIG. 5 is a right side view thereof;

FIG. 6 is a top view thereof, wherein the dashed lines represent a zipper covered underneath a rim portion of the holding case; and,

FIG. 7 is a bottom view thereof.
